DRAW-CORD WEAVING MECHANISM FOR
TEXTILE LOOMS

Charlton Hudson Williams, Columbus, Ga., assignor to Swift Manufacturing Company, Columbus, Ga., a corporation of Georgia

Application December 9, 1947, Serial No. 790,469

10 Claims. (Cl. 139—55)

1

The present invention relates to improvements in draw-cord weaving mechanism for textile looms and has for an object to provide a mechanism for weaving a draw-cord into the leno material in accordance with a prearranged plan in which the draw-cord will have the necessary freedom of movement in the woven material to permit it to function as a draw-cord, for instance in connection with bags or sacks containing oranges and the like material.

Another object of the invention is to provide a draw-cord weaving mechanism of a unitary character suitable for installation in existing looms without material structural modifications of the same.

The invention further contemplates the provision of a mechanism which may be installed on either a Draper type cam loom or on a Crompton and Knowles box loom or other type of loom which will be economical to install and maintain.

Heretofore it has been the practice to insert draw-cord into leno material by unskilled labor which has been found to involve considerable expense in the manufacture thereof, and it is a further object of the present invention to provide automatic mechanism for the weaving of draw-cord at the same time leno material is being woven and at greatly reduced expense.

With the foregoing and other objects in view, the invention will be described more fully hereinafter and more particularly pointed out in the appended claims.

In the drawings in which the same reference characters are used to denote the same parts throughout the several views:

Figure 1 is a vertical transverse section taken through the frame of a cam loom wherein a draw-cord weaving device constructed in accordance with the present invention is installed.

Figure 2 is a fragmentary vertical longitudinal section taken on the line 2—2 in Figure 1.

Figure 3 is a fragmentary horizontal section taken on the line 3—3 in Figure 2.

Figure 4 is a fragmentary perspective view of the improved draw-cord weaving mechanism.

Figure 5 is a fragmentary side elevational view taken at the rear portion of the cam loom showing the placement of the supply of draw-cord on the loom with the friction strap removed.

Figure 6 is a fragmentary end elevation of the loom taken from the right hand end of Figure 5.

Figures 7, 8, 9 and 10 are side elevational views 55 ers 54 may be in the form of set collars.

2

of the cam and follower showing the various successive phase positions thereof.

Figure 11 is a fragmentary perspective view of a modified form of the present invention as installed on a Crompton and Knowles box loom.

Figure 12 is a side elevational view of a form of bracket employed in the modified device.

Figure 13 is a fragmentary top plan view of the bracket together with stud broken away.

Figure 14 is a side elevational view of a form of frame support for the bracket, and

Figure 15 is a top plan view of the same.

Referring more particularly to the drawings, and for the present to that form of the invention shown in Figures 1 to 10 inclusive, 20 designates a conventional lay sword affixed to a lay sword shaft 21 journaled in bearings 22 and 23 on the loom frame members 24 and 25.

An arm 28 adjacent the lay sword 20 is also affixed to the lay sword shaft 21 and fixedly carries a pawl shaft 27 on which is rotatably supported a pawl 28 having at its free end a tooth 29 for sliding over and engaging the ratchet teeth 30 on a ratchet wheel 31. Such ratchet wheel 31 is affixed to a cam shaft 32. The cam shaft is mounted in bearings 39 and 40 upon appropriate parts of the loom frame and intermediate its ends such shaft carries fixedly thereon a cam 33 having a low point or a low side 34 and a high point or lobe 35 which may be approximately semi-circular in length in the form shown in the invention.

Also affixed upon the cam shaft 32 are one or more brake drums 36 over which frictionally engage the brake bands or straps 37 tensioned by coil or other springs 38 which may engage about parts of the loom framework.

The cam is engaged by a follower which may be in the form of one or more rollers 43 journaled on a pin 42 carried by the free end of an arm 41 loosely mounted to rotate about the lay sword shaft 21. To the pin 42 is connected a strap 44 which as more particularly shown in Figures 1, 2 and 5 is suspended at the lower end of a harness wire 45 having an eyelet 46 through which passes the draw-cord 47. The harness wire 45 is carried by a flexible strap 48 trained over guide spools 49 rotatably carried upon guide spool shafts 50 supported in the upper end of the arch 51 as by clamps and bolts 52 and 53 respectively. This latter structure is shown to advantage in Figure 2, from which it will also be seen that spacers 54 maintain the spools 49 in proper position on the shafts 50. These spacers 54 may be in the form of set collars.

The other end of the strap 48 carries a harness wire 45^a having an eyelet 46^a to receive a second draw-cord 47^a. The lower end of the harness wire 45^a is connected to the upper end of a coil spring 55 through a strap 77. The lower end of the coil spring 55 is anchored to a part of the framework.

Referring more particularly to Figures 5 and 6, a warp beam 78 is shown as carrying a mass of warp 79 receivable over a whip roll 63 carried in the conventional whip roll support 51. In the customary manner the warp is carried forwardly from the whip roll to the usual harness (omitted for clearness). The draw-cord harness 45, 45^a is situated close to the conventional harness and heddle frames for the warp mass 79.

A supply of draw-cord is contained on a spool 68 which may be removably mounted upon a shaft 59 which is removably journaled in bearing supports 58 and 58^a carried by the loom frame 24 preferably above or adjacent the warp beam 78 as best seen in Figures 5 and 6; whereby the draw-cord 47 may be led from the spool 68 down and passed beneath the whip roll 63 and thence brought forwardly over the upper side of the whip roll 63 to take its place alongside the warp mass 79; it being understood that this draw-cord 47 is in alignment with the eyelet 46 of the draw-cord harness wire 45. Where a second draw-cord 47^a is to be woven, a second draw-cord supply spool will be mounted at the opposite side of the loom in alignment with the eyelet 46^a of the draw-cord harness wire 45^a.

A friction strap 61 is in any desired manner laid over the spool 60 so as to impose necessary friction on the drum 60 to prevent overrunning of the same. The friction strap 61 is connected by springs 62 with parts of the framework to impose the necessary tension on the strap 61 and the drum or spool 60.

When the supply of draw-cord is exhausted and requires replenishing, the shaft 59 may be lifted from the open bearing 58 and drawn axially out from the inner bearing 58^a, it being understood that the friction strap 61 is first disengaged from the spool 60. Such spool 60 may then be slid off the shaft 59 and a full spool 60 take its place and the shaft 59 be restored to the bearings by first introducing the inner end of the shaft into the closed bearing 58^a and thereupon drawing the outer end of the shaft into the open bearing 58. The strap 61 can then be lifted over the drum and the draw-cord 47 drawn down and around the whip roll 63 and threaded through its harness.

In operation, with a supply of the draw-cord in place and threaded through its harness, the loom is set in motion in the ordinary manner. As the lay sword 20 continuously rocks fore and aft to beat up the lay, the arm 28, shaft 27 and pawl 29 partake of this same oscillating movement by which in its rear movement the pawl tooth 29 slides over the inclined wall of a tooth 30 of the ratchet wheel 31 to engage behind a shoulder of the next adjacent tooth. On the forward movement of the lay sword 20, the pawl 26 will be correspondingly drawn forward through the same arc of movement pulling upon the ratchet wheel 31 thereby imparting rotation to the cam shaft 32 through an angular distance corresponding to the radius of arm 28 which is calculated with reference to the size and arrangement and number of teeth 30 of the ratchet wheel 31 to move the cam shaft 32 a distance corresponding to one pick of the loom. Thus at each

forward stroke of the lay sword 20 the cam shaft 32 will be given an angular rotation corresponding to one pick of the loom, by way of example the ratchet wheel 31 is shown to have 12 teeth 5 and the high point of the cam 35 to be a substantial semi-circle. Consequently six picks of the loom will take place while the high point 35 of the cam is rotating continuously in contact with the cam follower 43 and holding the same depressed. Figures 4 and 8 show the high point or lobe 35 of the cam as having just engaged the follower roller 43, such follower roller being at its maximum depressed position in which it has pulled down the strap 44 and the harness wire 45 so that the draw-cord 47 is pulled down to the bottom of the shed thereby permitting the passage of the weft thread thereover. In pulling the harness wire 45 down the companion harness wire 45^a is elevated to the top of the shed so that the weft passes beneath the other draw-cord 47^a. The spring 55 is expanded and put under tension.

This condition prevails during the entire time that the high point 35 of the cam is rotating in contact with a cam follower roller 43. In the example shown in the drawings this interval is one of 180° corresponding to six teeth 30 on the ratchet wheel 31, or in other words one half of the number of teeth on the ratchet wheel 31. Thus the draw-cord 47 and 47^a will be held in these positions during six picks of the loom.

Figure 7 shows the flat side 34 of the cam as engaging the follower roller 43 when the follower roller is in its uppermost position. It requires one pick to move from the position of Figure 7 to the position of Figure 8. Figure 9 shows the high point of the cam 35 having covered a distance of approximately three picks. Figure 10 shows the high point of the cam having moved six picks and freed the cam follower 43 which is thereupon pulled upwardly by the spring 55 acting through the harness and strap linkage.

Figure 1 shows the spring 55 in its expanded position with the eyelet 46^a elevated above the shed or weft race and the eyelet 46 depressed beneath the same. However when the parts are in the position shown in Figure 10 the coil spring 55 pulls down the eyelet 46^a and its entrained draw-cord 47^a and correspondingly elevates the eyelet 46 and the opposite draw-cord 47 so that the same are respectively below and above the raceway or shed for a time interval. The low point of the cam also being of an arcuate length of 180° in the example shown in the drawings. The draw-cord will remain in this position for six picks until the parts again arrive at the relative positions shown in Figure 7. Thus the draw-cord is woven into the material alternately at a spaced distance of six picks which gives the same the requisite looseness for pulling through the material in the character and function of a draw-cord such for instance as for puckering and crimping the bag to close the same.

It will be understood that the draw-cord may be woven into the leno material at any other suitable pick distance. In selecting any other pick distance for the interweaving of the draw-cord it will be noted that it is necessary to provide a ratchet wheel 31 having twice the number of teeth 30 as the number of picks desired to be woven.

Referring more particularly to that form of the invention illustrated in Figures 11 through 15 inclusive, the invention is shown as applicable to a Crompton and Knowles box loom having a conventional whip roll 63^a which has been modified

according to the invention by providing its end portions 64 with knurling or other roughened surface parts.

According to the invention one or more rollers 65 is mounted at one or both sides of the loom frame. A roller 65 is mounted above the whip roll 63^a in such relation that the peripheral surface of the roller 65 rests with its weight upon the knurled portion 64 of the whip roll 63^a. Thus the rotary motion of the whip roll 63^a is imparted to the roller 65. The roller 65 is rotatably mounted on a stud 66 one end of which is carried by a bracket 67. Such bracket 67 has an elongated slot 68 adjustably received over a bolt 73 carried by a frame plate 71. A nut 74 is threaded upon that portion of the bolt 73 which projects inwardly beyond the bracket 67 for the purpose of binding the bracket 67 against the frame plate 71 so as not to permit the bracket 67 and the roller 65 to drop or rotate about the bolt 73. This binding engagement between the parts 67 and 71 also prevents the bracket 67 from sliding forwardly on the bolt 73 which would permit the roller 65 to back away from the whip roll 63^a. A spacing sleeve 72 welded or otherwise affixed to the plate 71 and to the loom frame 24^a serves to maintain the plate 71 in a proper inwardly set position to receive the bracket 67. A draw-cord spool support 58^b is bolted or otherwise affixed to the loom frame 24^a and carries a shaft 59^a, which in turn rotatably supports a draw-cord spool 60^a which contains a supply of the draw-cord. A friction strap 75 is laid over the spool 60^a or the supply of draw-cord thereon and carries at its lower end a weight 76 by which to impose the necessary friction tension on the spool 60^a. The upper end of the strap 75 is affixed to a suitable part of the loom frame.

An eye guide 70 is carried by an arm 69 which projects down diagonally from the rear end portion of the bracket 67. As shown in Figure 13 the stud 66 may have a reduced threaded end 80 threaded directly into the bracket 67 or as shown in Figure 13 having a nut 81 thereon for holding the same to the bracket.

The draw-cord 47^b is shown in Figure 11 as being drawn down from the spool 60^a through the eye 70 and thence on to the knurled portion 64 of the whip roll 63^a and through the bight or nip between the whip roll 63 and the pressure roller 65. From this point the draw-cord 47^b is carried forwardly to its harness.

This mechanism is designed to weave in an amount of draw-cord 47^b in excess of the material being woven. To this end during the initial threading operation of the draw-cord in the heddles and harness, an appreciable amount of slack in the draw-cord 47^b is left between the whip roll 63^a and the harness frame. This slack is maintained throughout the weaving operation due to the fact that the draw-cord has a positive feed through the knurled portion 64 of the whip roll 63 and the pressure roller 65. The whip roll 63^a is rotated in the usual manner by the warp mass passing thereover.

What is claimed is:

1. For use with a loom having a vibratory member, a mechanism for weaving draw-cord in the material woven by the loom comprising a harness for the draw-cord biased to a predetermined shedding position, a cam follower coupled to said harness, a rotary cam for said cam follower having a high point adapted to shift said harness to a subsequent shedding position, an intermittent motion device coupled to rotate said

cam and coupled to receive its motion from the vibratory member, and spring means coupled to said harness for biasing the harness to the predetermined shedding position and also for drawing the cam follower against the high point of the cam.

2. A mechanism for weaving draw-cord as claimed in claim 1 characterized by the fact that said harness has a plurality of harness wires spaced apart in the fabric being woven by the loom and receiving a plurality of draw-cords woven in the fabric on laterally spaced lines.

3. For use with a conventional loom having a lay sword and its rocking shaft, a mechanism for weaving draw-cord in the material woven by the loom comprising an arm fixed to rock with the lay sword shaft, a pawl pivotally carried by said arm, a ratchet wheel having a predetermined number of inclined and shouldered ratchet teeth engaged by said pawl for transmitting step by step rotation to the ratchet wheel on vibratory motion of said arm, a cam shaft on which said ratchet wheel is affixed, a cam affixed to said cam shaft, a cam follower for said cam, a pivotally mounted arm carrying said cam follower, a harness for the draw-cord biased to a predetermined shedding position and coupled to said cam follower, a brake drum affixed to said cam shaft, and a resiliently tensioned brake band about said drum.

4. For use with a loom having the conventional harness and lay member, a mechanism for weaving draw-cord in the material woven by the loom comprising a pair of eyeleted heddle wires arranged in substantially spaced parallel relation, a connecting strap between said heddle wires, means for movably supporting said strap in the upper portion of the loom frame, spring means connected to the lower end of one of the wires for biasing the harness to a predetermined shedding position, and means operable by the lay member of the loom and for relatively reversing the predetermined shedding position of said harness wires.

5. For use with a loom having conventional shedding and lay members, a mechanism for weaving draw-cord in the material being woven by the loom comprising a draw-cord harness for receiving the draw-cord, means operable by the lay member of the loom for operating the harness to raise or lower the draw-cord above or below the shed being formed by the conventional loom shedding motion, and a positive feeding device for feeding the draw-cord to the harness.

6. A mechanism for weaving draw-cord as claimed in claim 5 characterized by the fact that the positive feed device comprises a whip roll having a roughened portion over which the draw cord passes, a pressure roll engaging the roughened portion of said whip roll, and means for guiding the draw cord from a source of supply through the bight between the roughened portion of the whip roll and said pressure roll.

7. A mechanism for weaving draw-cord as claimed in claim 6 further characterized by the fact that the pressure roller is carried by a bracket longitudinally and pivotally adjustable about the loom frame and having a device to secure the bracket in fixed position.

8. A mechanism for weaving draw-cord as claimed in claim 7 in which said bracket has a diagonal downwardly extending arm carrying a guide eye for the draw-cord adjacent the bight between the whip roll and pressure roller.

9. For use with a loom having the conventional

harness and lay member, a mechanism for weaving draw-cord in the material woven by the loom comprising an eyeleted heddle wire adapted to receive the draw-cord, resilient means connected to one end of the heddle wire for biasing the same to a predetermined shedding position, and means operable by the lay member of the loom for relatively reversing the predetermined shedding position of said heddle wire.

10. For use with a conventional loom having a lay sword and its rocking shaft, a mechanism for weaving draw-cord in the material woven by the loom comprising an arm fixed to rock with the lay sword shaft, a pawl pivotally carried by said arm, a ratchet wheel having a predetermined number of inclined and shouldered ratchet teeth engaged by said pawl for transmitting step by step rotation to the ratchet wheel on vibratory motion of said arm, a cam shaft on which said ratchet wheel is affixed, a cam affixed to said cam shaft, a cam follower for said cam, a pivotally mounted arm carrying said cam follower, a harness for the draw-cord biased to a predetermined shedding position and coupled to said cam follower, and braking means on said cam 25

shaft for preventing overthrow of the cam by the pawl.
